UNITED STATES PATENT OFFICE.

THEODORE B. SCHULTE, OF CLEVELAND, OHIO.

DAVENPORT-BED.

1,093,565.

Specification of Letters Patent. Patented Apr. 14, 1914.

Application filed September 16, 1912. Serial No. 720,466.

To all whom it may concern:

Be it known that I, THEODORE B. SCHULTE, a citizen of the United States of America, residing at Cleveland, in the county of Cuyahoga and State of Ohio, have invented certain new and useful Improvements in Davenport-Beds; and I hereby declare the following to be a full, clear, and exact description of the invention, such as will enable others 10 skilled in the art to which it pertains to make and use the same.

This invention relates to new and useful improvements in davenport beds and particularly to an improvement on the bed shown 15 in my pending application Serial No. 641,281.

The object of this invention is to provide an article of the character indicated which can be cheaply manufactured and which will 20 be simple in construction, durable and easily operated.

A further object of my invention is to provide an article of this kind which will take up much less room than articles of this kind 25 now on the market.

My invention, therefore, consists in the features of construction and combination and arrangement of parts, described in the specification, pointed out in the claims and 30 illustrated in the accompanying drawings.

Referring to the drawings Figure 1 is a front elevation of a davenport embodying my invention. Fig. 2 is a rear elevation of the same. Fig. 3 is a section on line 3—3, 35 Fig. 1. Fig. 4 is a central longitudinal section showing the bed portion extended as when in use. Fig. 5 is a detail view of a portion of the bed. Fig. 6 is a section on line 6—6, Fig. 4. Fig. 7 is a section on line 40 7—7, Fig. 3. Fig. 8 is a detail view of the catch for holding the bed sections in their proper positions when extended. Fig. 9 is a view in perspective showing a portion of the back of the bed.

45 Referring to the drawings it will be seen that the main frame comprises four uprights or posts 1, a pair of top side bars 3, a pair of bottom side bars 4, a rear top bar 5, a rear bottom bar 6 and a front bottom bar 7. The 50 sides of the frame are not filled in with upholstery, but are left open to insure a circulation of air. On each of the bottom side bars 4 is arranged a track 11, for supporting the spring mattress sections, as will be described later. The mattress itself is made in

three sections, each section having a separate frame, shown at 12, 13 and 14. The section 12 is pivotally supported at its inner end between the rear posts of the main frame by means of hanger plates 15, each of which has 60 a small trunnion 16 which enters a hole in the adjacent side of the frame of the said mattress section. The hanger plates are secured to the said posts by means of screws and by simply adjusting the position of the 65 plates backward or forward or up or down the mattress section can be readily adjusted to its proper position in the main frame. The section 12 is divided by a transverse bar 18 into two portions and the portion between 70 the bar 18 and the pivoted end of the section is provided with a cover 19 of any suitable material so that a compartment 20 is formed. The portion between the bar 18 and the front or free end of the section is upholstered on 75 one side, as indicated at 22. Now when the section is in the position illustrated in Fig. 4 the said section forms the first or head section of the mattress, but when the said section is swung up to the vertical position, 80 shown most clearly in Fig. 3, the said section forms the back of the davenport and the upholstered portion 22 forms the upholstery for the back of the davenport and the compartment 20 forms a place in which pillows and 85 the like may be stored.

In order to assist the lifting of the pivoted section 12 a pair of coil springs 24 are secured to the rear end of the said section and the said springs are also secured to the rear 90 bottom bar 6 of the main frame. Between the springs 24 a pair of bow-springs 25 are arranged, one end of each bow-spring being secured to the bar 6 and the other end of each bow-spring being operatively connected 95 with the rear end of the section 12 by means of a coil spring 26 and said springs 26 are made stronger than the springs 24. On the bar 6, just above each bow-spring 25, is arranged a small block 27 which has an upwardly and outwardly inclined face. The object of the blocks 27 is to cause an upward and outward movement of the bow-spring when the section 12 is lowered and a downward and inward movement when the section 100 is raised, and the movement of said springs swing out or in the lower ends of the connecting coil springs 26, so that said coil springs 26 remain vertical during the lowering and raising of said section. Now, when 105

the pivoted section is brought to a horizontal position, all the springs are put under tension and particularly the larger coil springs 26 connected with the bow-springs 25 and 5 the tension of the springs is such that the said springs more than counterbalance the weight of the mattress section 12 and if the mattress section be not held down after being lowered to the horizontal position the 10 front end will be swung up and held a distance of twelve or fourteen inches above the main frame. Then as the springs will still be under tension a very slight force will cause the section to swing up the rest of the 15 way until it assumes a vertical position. Stops 28 are mounted on the rear posts of the main frame to prevent the section 12 from swinging too far back when raised.

The central mattress section 13 is adapted 20 to rest on or be supported by tracks 11 in the main frame when the bed is closed and the frame of the said section 13 is provided on its bottom with a series of rollers 29, which engage said tracks 11, so that the 25 said section can be easily pulled out or shoved back on the said tracks. This section 13 is provided with a pair of legs 30 which are hinged to the front part of the frame so that they can fold up at each side 30 of the frame. When the said section 13 is pulled out the front end thereof is supported by the said legs while the rear end remains supported in the main frame by the means which will now be described:—A pair of 35 track forming bars 31 are arranged to extend between the rear bar 6 and the front bar 7 of the main frame. The said bars 31 are slightly inclined forwardly and have seat forming depressions 32 at their front ends. To the rear end of the mattress section 13 is hinged a supporting member 33 which in this case consists of a board which extends from side to side of the mattress section. To the rear face of the supporting 45 member 33 are secured a pair of brackets 34 and on each bracket is mounted a U-shaped spring 35 which extends downwardly at an angle to the supporting member and the lower portion of each spring always remain 50 in contact with the adjacent bar 31. The operation of this supporting member 33 will be understood by referring to Figs. 3 and 4. In Fig. 4 the mattress section 13 is shown drawn out from the main frame and when 55 the section is in this position the supporting member 33 extends down from the section 13 at a slight inclination and the lower edge thereof rests in the seats 32 and the lower ends of the springs 35 rest on the 60 bars 31. Now when the section 12 is raised by the means hereinafter described and the section 13 is moved, to push it back into the main frame, the supporting member 33 folds down against the tension of the 65 springs 35 and the end of the section 13

sinks down until the rollers on the bottom thereof engage the rails 11 and as the section is pushed farther back into the main frame the supporting member 33 remains folded close against the bottom of the said section 13. Now when the section 13 is pulled 70 out the roller on the bottom of said section will travel on the rails 11 until the lower edge of the supporting member 33 comes in contact with the front walls of the seats 32 and said lower edge of said supporting member will slip down into said seats 32 and the forward movement of the support being thus arrested the support will swing up to an approximately vertical position in which 75 movement it will be assisted by the springs 35, and thereby raises the rear end of the mattress section 13.

The method of connecting the section 13 or the center section with the section 12 or first section is as follows:—One end of an iron bar 42 is pivotally secured near the middle of the first section 12, as at 43, and to the opposite end of said bar 42 is secured one end of a small link 44, the other end of 80 which is pivotally secured to the rear end of the section 13 at the center thereof. When the device is used as a davenport, the section 12 will be in a vertical position and the section 13 will be in a horizontal position 85 and resting entirely on the main frame. If it is desired to place the sections in their proper position for using the device as a bed the section 13 is pulled forward and while the section 13 is being drawn out it will pull down the section 12 by means of the bar 42 and connecting link 44, so that the said section 12 will swing down into the 90 place formerly occupied by the section 13.

Now, as before mentioned, the tension of 95 the counterbalancing springs is sufficient to hold the front end of the section 12 in a position intermediate its vertical and horizontal positions and in order to hold the said section down in a horizontal position the following means is provided:—At the center of the rear end of the section 13 is pivotally mounted a hook 47 which is adapted to engage the front end of the section 12. On the hook 47 is arranged a strap 48. Through the strap 48 is passed one end of a 100 rod 49 and in the end of the rod is secured a pin 50. The rod 49 extends to the front end of the mattress section 13 and on the front end of said rod 49 is secured a ring 105 51. Now when it is desired to lock the two sections together the rod 49 is shoved back which causes the hook 47 to swing down and engage the front end of the mattress section 12. When it is desired to disengage the sections the rod 49 is pulled forward and when the pin 50 on the inner end of said rod strikes the strap 48 it causes the hook 47 to 110 swing out of engagement with the front end of the mattress section 12.

The end or foot section 14 is hinged at its rear end to the center section by means of hinges 57 of the usual construction so that the said section 14 can be folded over on top 5 of the section 13. The side which is up when the section 14 is folded over on the section 13 is upholstered to form the seat of the davenport. At its front end said section 14 is provided with a pair of legs 58 which 10 are secured thereto by pivot pins so that when the said section 14 is folded back on the section 13 the said legs can be swung out of view. At the end of the section 14, opposite to the hinged end, a clamping device is provided for engaging the ends of the bed covers, which is arranged as follows:—In the end frame of the section are formed several grooves 60, shown most clearly in Fig. 5, and to said end is hinged 15 a plate 61 which is arranged to overlap said grooves. A spring 62 is provided for holding the plate 61 against the end board. To secure the covers the plate 61 is pulled back and the ends of the covers are inserted between the plate and the end of the bed section, and the plate is then released and the spring 62 clamps it against the ends of the 20 covers.

The operation of the device will be readily understood from the foregoing description.

If the device is being used for a davenport, as shown in Fig. 1, and it is desired to convert it into a bed, as shown in Fig. 4, 35 it is only necessary to take hold of and pull out the section 13, as far as it will come. As the section 13 moves out the rear end thereof will be lifted up by the upward swing of the supporting member 33 so that the rear end 40 of the bed is raised to the height it occupies when the bed is open. After the section 13 has been pulled out the legs 30 are swung down so as to support the front end. Now as the section 13 moves out the section 12 45 will be swung down from its vertical position by the means before described but will remain slightly tilted above the rear end of the frame 13. The front end of the section 12 is then pressed down by hand and the rod 49 is shoved back so that the hook 47 engages the front end of the section 12 locking 50 the said section down. The section 14 is then folded down parallel with the section 13 and the legs at the front end thereof are 55 swung down to support the same. When it is desired to reconvert the bed into a davenport the section 14 is folded over on the section 13, the rod 49 is pulled out disengaging the hook at the front end of the section 12 60 and permitting the section 12 to swing up. The section 13 is then pushed back and as it moves back the supporting member 33 will swing down allowing the rear end of the section 13 to move down until the rollers on 65 the bottom thereof come in contact with the

tracks 11, and as the said section is pushed farther back into the main frame it will shove up the section 12 by the means before described until the said section assumes a vertical position forming the back of the 70 davenport.

In order to conceal the front end of the section 13 and give a finish to the front of the davenport I provide a front board which consists of two sections 65 and 66 which are 75 secured together by means of hinges 67. The section 65 is provided at each side near its lower edge with a small trunnion 68 which has a bearing in the adjacent side post of the main frame, and at each side of the same section 65, near the top edge, is mounted a spring bolt 69, the end of which is adapted to enter a socket 69' in the adjacent side post. A cord 70 is connected to each bolt and the cords are carried over 80 small rollers 71 and through an eye 72 and a small ring is secured at the ends of the cords to provide a grip piece therefor. By pulling the said cords the bolts can be withdrawn from the sockets in the side posts. 85 At the top edge of the section 66 are secured a number of small plates 73 which project beyond the edge, and at the front edge in the bottom of the frame 14 are formed a series of sockets 74 arranged to receive the projecting ends of said plates. The outer face of the section 66 is preferably upholstered, 90 as shown at 75.

In order to provide means for supporting the bed coverings when not in use a bar 78 100 is provided which extends between the rear side posts of the frame. This bar 78 has crank arms 79 at each end thereof which are supported in small journals 80 mounted on the posts. At the end of each arm 79 is a 105 stop forming member 81. When the bed is closed the bar will extend a little at the rear of the supporting posts and the stops on the crank arms will hold the arms out at a right angle to the rear face of said posts. Now 110 when the bed is open and it is desired to place the coverings on the bar the bar is swung around on the crank arms so that it is brought in toward the front of the supporting posts making it readily accessible. 115

What I claim is,—

1. In a device of the character indicated, a main frame, a head mattress section pivotally supported in said main frame and capable of being raised to a vertical position to form a seat back or lowered to a horizontal position to form a bed section, a middle mattress section slidably mounted in said main frame in a plane below the plane occupied by the head section when 120 said section is in a horizontal position, means supported by the main frame and operatively connected with said middle section for raising said middle section to the plane of the head section when said middle section 125 130

- is pulled out and means for supporting the front end of said middle section.
2. In a device of the character indicated, a main frame, a head mattress section pivotally supported in said main frame and capable of being raised to a vertical position to form a seat back or lowered to a horizontal position to form a bed section, a middle mattress section slidably mounted in said main frame in a plane below the plane occupied by the head section when said section is in a horizontal position, means supported by the main frame and operatively connected with said middle section for raising said middle section to the plane of the head section when said middle section is pulled out, means for supporting the front end of said middle section, a foot mattress section hinged to said middle section and capable of being either folded over on top of said middle section or folded down beyond said middle section to form a horizontal continuation of said middle section and legs operatively connected to the front end of said foot section.
3. In a device of the character indicated, a main frame, a head mattress section pivotally supported at its rear end at the rear end of said main frame and capable of being raised to a vertical position to form a seat back or lowered to a horizontal position to form a bed section, a horizontally arranged middle mattress section slidably mounted in said main frame in a plane below the plane occupied by the head section when in a horizontal position, a supporting member pivotally secured at one end to said middle section and having its other end supported by the main frame and adapted to slide in the main frame when the middle section is pulled out or shoved back into the main frame, means for arresting the forward movement of said supporting member so as to cause said supporting member to swing up and raise the rear end of the middle section and means for supporting the front end of the middle section.
4. In a device of the character indicated, a main frame, tracks arranged in said main frame at each side thereof and extending from the front to the rear thereof, a bar arranged in the main frame intermediate of said tracks and extending from the front to the rear thereof, a head mattress section pivotally supported in the main frame and capable of being raised to a vertical position to form a seat back or lowered to a horizontal position to form a bed section, said head mattress section when in a horizontal position occupying a plane a distance above said tracks, a horizontally arranged middle mattress section adapted when in said frame to rest on said tracks, a supporting member pivotally secured to the rear end of said middle mattress section, the lower end of said supporting member being arranged to

travel on the said bar, a spring connected to said supporting member and engaging said bar and arranged to resiliently resist the folding of said supporting member down on said bar, means for arresting the forward movement of the lower end of said supporting member and means for supporting the front end of said middle mattress section.

5. In a device of the character indicated, a main frame, tracks arranged in said main frame at each side thereof and extending from the front to the rear thereof, a pair of bars arranged in the main frame intermediate of said tracks and extending from the front to the rear thereof and having seats at their front ends, a head mattress section pivotally supported in said main frame and capable of being raised to a vertical position to form a seat back or lowered to a horizontal position to form a bed section, said head mattress section when in a horizontal position occupying a plane a distance above said tracks, a horizontally arranged middle mattress section adapted when in said frame to be supported by said tracks, rollers arranged on the bottom of said middle mattress section and adapted to travel on said tracks, a supporting member pivotally secured to the rear end of said middle mattress section, the lower end of said supporting member being arranged to travel on the said bars and rest in said seats at the front ends of said bars, a spring connected to said supporting member and engaging said bars and arranged to resiliently resist the folding of said supporting member down on said bars and means for supporting the front end of said middle mattress section.

6. In a device of the character indicated, a main frame, a head mattress section pivotally supported in said main frame and capable of being raised to a vertical position to form a seat back or lowered to a horizontal position to form a bed section, a middle mattress section slidably mounted in said main frame in a plane below the plane occupied by the head mattress section when said section is in a horizontal position, means supported by the main frame and operatively connected with said middle section for raising said middle section to the plane of the head section when said middle section is pulled out, means operatively connecting the head section and the middle section so that the pulling out of the middle section will draw the head section down from its vertical position and the shoving back the middle section will raise the head section to its vertical position and means for supporting the front end of said middle section.

7. In a device of the character indicated, a main frame, a head mattress section pivotally supported at its rear end at the rear end of said main frame and capable of being raised to a vertical position to form a seat

back or lowered to a horizontal position to form a bed section, a horizontally arranged middle mattress section slidably mounted in said main frame in a plane below the plane 5 occupied by the head section when in a horizontal position, a supporting member pivotally secured at one end to said middle section and having its outer end supported by the main frame and adapted to slide in the 10 main frame when the middle section is pulled out or shoved back into the main frame, means for arresting the forward movement of said supporting member so as to cause said supporting member to swing 15 up and raise the rear end of the middle section, means operatively connecting said middle section and said head section so that the pulling out of the middle section will draw the head section down from its vertical position and the shoving back of the middle section will raise the head section to its vertical position consisting of a bar pivotally secured near the middle of the head section at the side thereof which is down when said 20 head section is in a horizontal position and operatively connected to the middle section at the rear end thereof, means for supporting the front end of said middle section, a 25 foot mattress section hinged to said middle section and capable of being either folded over on top of said middle section or folded down beyond said middle section to form a horizontal continuation of said middle sec- 30

tion and legs operatively connected to the front end of said foot section. 35

8. In a device of the character indicated, a main frame, a head mattress section pivotally supported at its rear end at the rear end of said main frame and capable of being raised to a vertical position or lowered to a horizontal position, means for counterbalancing said section so as to normally hold said section in a position intermediate its vertical and horizontal positions, a middle mattress section arranged to form a continuation of the head mattress section when the head mattress section is in a horizontal position and means for locking the said sections together, said means comprising a hook pivotally secured at the rear end of the middle 40 section and adapted to engage with the front end of the head section, a strap arranged on said hook, a rod extending from the front end of the middle mattress section to the rear end thereof, the inner end of said rod 45 passing through said strap and a pin arranged in the inner end of said rod to prevent its withdrawal from said strap. 50

In testimony whereof, I sign the foregoing specification, in the presence of two witnesses. 55

THEODORE B. SCHULTE.
